UNITED STATES PATENT OFFICE

THOMAS E. MURRAY, JR., OF BROOKLYN, NEW YORK, ASSIGNOR TO MURRAY RADIATOR CORPORATION, A CORPORATION OF NEW YORK

RADIATOR

Application filed May 12, 1926. Serial No. 108,488.

In an application of Thomas E. Murray, No. 709,080 filed April 26, 1924, (Patent No. 1,744,078, granted January 21, 1930), there is described a radiator designed to produce a very much increased circulation of air as compared with radiators of the standard type and also to provide a large heating capacity in proportion to the floor area and weight of the radiator, and having other advantages set forth in said application.

The present application is directed to certain improvements which are especially advantageous in connection with radiators of the type described in the aforesaid application and which are advantageous also with other types of radiator.

The accompanying drawings illustrate embodiments of the invention.

Fig. 1 is a side elevation of a complete radiator;

Fig. 2 is an end elevation of the same with a front panel in section;

Fig. 3 is a side elevation of part of the radiator with a certain front panel omitted;

Fig. 4 is partly a plan and partly a section of the righthand end of the same;

Fig. 5 is a front elevation of a modified construction;

Fig. 6 is a partial plan and a partial section of an end of the same with the addition of a front panel;

Fig. 7 is a partial end elevation and a partial section of the same;

Fig. 8 is a perspective view of the radiating structure;

Fig. 9 is an elevation partly in section of a strip heater;

Fig. 10 is a view similar to Fig. 7 of a radiator made with a strip heater.

Referring to the embodiment of the invention illustrated in Figs. 1 to 8, the heating element is a steam conduit in the form of a continuous and preferably jointless copper tube of comparatively small diameter arranged in a plurality of sections 1, 2, 3, 4, 5, (shown in Fig. 5) extending back and forth lengthwise of the radiator, with bends 6 at alternate ends. Heating elements of other types may be used such as the narrow elongated electric resistance element of the co-pending

Murray application No. 96,699 filed March 23, 1926, for example. Such a design is illustrated in Figs. 9 and 10. The strip heater 1^a is an elongated metal casing containing a strip of metal of high resistance connected to the terminals 1^b at opposite ends. But the present invention is of particular value in connection with the continuous tubing illustrated. Also various other arrangements of the conduit may be provided and it may be of copper as stated, or of wrought iron, steel, brass or other suitable metal. It is preferably enclosed in the radiating structure except at the projecting ends which carry couplings 7 and 8 for attachment to discharge and supply pipes.

The radiating structure is made of sheet metal, preferably thin sheets of copper, corrugated in the horizontal plane and embracing the conduit at opposite sides with a good contact so as to absorb heat efficiently therefrom, and in such a way as to provide flues through which the air ascends rapidly as it is heated.

Other metals than copper may be used for the radiating structure as well as for the conduit, though copper has special advantages in conducting and radiating qualities and and thinness or lightness.

In plan view, Figs. 4 and 6, it will be seen that the radiating structure has narrow longitudinal portions 9 connected to oppositely inclined outwardly extending portions 10 connected at their outer edges by narrow longitudinally extending portions 11. These parts may be of various angles and of various dimensions and may be curves merging into one another instead of the distinct straight lines shown. The parts at both sides of the radiator may be made of a single sheet of metal with a portion 12 extending over the end so as to provide an attractive smooth finish at this point. The same principle may be applied at both ends, using separate plates which overlap or meet at an intermediate point. And, in fact, the radiating structure may be made up of various numbers of plates arranged in various ways.

The inner portions 9 of the radiating structure are brought into contact with each

other from opposite sides so as to form complete separate flues 12, 13, 14, and so forth, for the upward passage of the air. They also embrace the pipe around its entire circumference as shown at 15 in Fig. 7. (Or the electric heater as at 15^a in Fig. 10.) In order to do this, the parts 4 are pressed out to the rounded shape shown at 15 between the successive flues. In this operation the metal spreads laterally as at 16, Fig. 8, so as to increase the contact surface lengthwise of the pipe.

In building the radiator the pipe is bent in an ordinary bending machine and the sheets of metal are corrugated and stamped to the shape of Fig. 8 in any usual or suitable machine. Solder, tin or similar material is applied to the recesses 15. The parts are assembled and are then heated and pressed together, yielding slightly as the solder softens so as to make a good heat conducting joint over substantially all the meeting faces of the radiating structure with the pipe.

There are many such joints in the entire radiator, so that the strain of holding the parts together at each joint is comparatively slight. The pipe supports the internal pressure without any assistance from the surrounding radiating structure. It is of advantage in manufacturing that the sections of the pipe are all parallel to each other. This makes it possible to use a single pair of dies to make the joints along each section of the pipe in succession. Ordinary soldering will generally be sufficiently strong, but the joints may be made by welding, brazing or other methods which make a joint that is entirely external to the pipe. The described machine and process for making the radiators are covered in a co-pending application of Murray & Hoffer, No. 91,023, filed February 27, 1926.

The surface area of the radiating structure can be substantially increased by making slits 17 (Fig. 3) therein and bending out and stretching the metal in opposite directions at opposite sides of each slit. Each slit increases the radiating surface by the length of the slit times twice the thickness of the sheet. I have found this to increase the efficiency in some designs up to as much as 16%. Instead of merely bending out the metal in a direction transverse to its plane, the slits may be staggered and the metal stretched in a direction parallel to its plane, making what is known as expanded metal. Or the metal may be bent as shown in the drawings and then with the aid of extra slits may be drawn out parallel with its plane to give a further increase of area and efficiency. This slitting and bending or stretching makes a radiating structure which is particularly useful in forced draft radiators. For a neat appearance it is preferable to have the end portions 18 (Fig. 4) unbroken.

While the slotted metal illustrated does not entirely close the flues 12, 13, it closes them sufficiently to maintain a draft upward.

In the design of Figs. 5, 6 and 7, the radiating structure is made of an unbroken sheet, which saves something in the cost of the radiator.

I prefer to apply a panel 19 to the front of the radiating structure. It improves the appearance and forms additional flues 20 and at the same time cuts off air which might pass through the slotted walls 10 into the flues 12 and 13 directly from the side. The front panel may be omitted, as in Fig. 5. It may be soldered, welded or brazed to the parts 11 of the radiating structure as shown in Fig. 4 or may be united by rivets 21 as shown in Figs. 6 and 7. It preferably has a flange 22 (Fig. 2) over the top corners of the radiating structure and side flanges 23 (Fig. 4) at the ends. Such a panel may be applied to the back as well as to the front. By uniting it directly to the radiating structure it takes heat therefrom and thus gives additional heating surface. It may be made of copper, steel or other metal and ornamented and finished in various ways.

The product is referred to as a radiator, and it has peculiar advantages particularly in efficiency, lightness and compactness as an ordinary radiator for heating the air in a room, but structures made on the same principle may be used not only for transferring heat or cold from the "heating element" to the air or other surrounding medium, but equally for transferring heat or cold from the surrounding medium through the radiating structure to a fluid within the heating element, as in the case of condensers in refrigerating plants, for example.

The radiator may be equally used for cooling air by circulating cold brine or the like through the pipes so that the latter become a heating element only in the negative sense, that is, they extract heat from the radiating structure and induce a flow of the cool air downward through the flues similar to the upward circulation of the air induced by the passage of steam through the pipes.

The steam or other heating medium may be admitted at one end of the pipe and discharged at the other as shown, or may be admitted and discharged through the same end as in the so-called "one-pipe" radiators. And instead of using a tube for the heating element a single box or vessel may be used with advantage in connection with some of the features of the present improvement. For example, a vessel may be used of the types shown in the Murray applications Nos. 725,559, filed July 12, 1924 and 43,444 filed July 14, 1925 (Patent No. 1,723,573, granted August 6, 1929).

Various other modifications may be made by these skilled in the art without departing

from the invention as defined in the following claims.

What I claim is:—

1. A radiator for heating the air of a room by steam or other high temperature heating medium comprising in combination a continuous tube in a number of sections one above another extending horizontally lengthwise of the radiator and a radiating structure applied to the sides thereof and corrugated in horizontal section, the inner portions of the corrugations substantially contacting with each other to form separate adjacent vertical flues for the passage of air about the tube and for inducing a rapid circulation of the heated air.

2. A radiator for heating the air of a room by steam or other high temperature heating medium comprising in combination a continuous tube in a plurality of sections one above another extending horizontally lengthwise of the radiator and a radiating structure applied to the sides thereof and corrugated in horizontal section, the inner portions of the corrugations substantially contacting with each other to form separate adjacent vertical flues for the passage of air about the tube and for inducing a rapid circulation of the heated air.

3. A radiator for heating the air of a room by steam or other high temperature heating medium comprising in combination a continuous tube in a plurality of sections one above another extending horizontally lengthwise of the radiator and a radiating structure applied to the sides thereof and corrugated in horizontal section, the inner portions of the corrugations substantially contacting with each other to form separate adjacent vertical flues for the passage of air about the tube and for inducing a rapid circulation of the heated air.

4. A radiator having a heating element and a radiating structure applied to the sides thereof and composed of sheet metal corrugated in horizontal section, the inner angles of the corrugated sheets engaging said heating element and the outer portions being slit and stretched to provide an increased surface.

5. A radiator having a heating element and a radiating structure applied to the sides thereof and composed of sheet metal corrugated in horizontal section, the inner angles of the corrugated sheets engaging said heating element and the outer portions being slit and bent out of the normal plane of the sheet.

6. A radiator for heating the air of a room, said radiator having a heating element, a radiating structure applied to the sides thereof corrugated in horizontal section to provide vertical flues for inducing a rapid circula-

tion of the heated air and a panel extending across and united to the corrugated structure so as to be heated thereby and exposed to the air on both its faces so as to provide an increased radiating surface.

7. A radiator for heating the air of a room, said radiator having a heating element, a radiating structure applied to the sides thereof corrugated in horizontal section to provide vertical flues for inducing a rapid circulation of the heated air and a panel extending across the corrugated structure and having a flange overlying the top corners of said structure.

8. A radiator for heating air of a room by steam or other high temperature heating medium comprising in combination a continuous tube in a plurality of sections one above another extending horizontally lengthwise of the radiator and a radiating structure united to the sides thereof and forming vertical flues which are closed in cross-section so as to induce a rapid circulation of the heated air.

9. A radiator for heating the air of a room, having a horizontally extending heating element and a radiating structure applied to the sides and corrugated in horizontal section to form vertically grooved front and back surfaces of the height and width of the radiator, said radiating structure being corrugated in horizontal section, the inner portions of the corrugations substantially contacting with each other to form separate adjacent vertical flues for the passage of air about the heating element and for inducing a rapid circulation of the heated air.

10. A radiator for heating the air of a room, having a heating element comprising a series of horizontally extending sections one above another and a radiating structure applied to the sides of said sections and corrugated in horizontal section to form vertically grooved front and back surfaces of the height and width of the radiator, the inner portions of the corrugations substantially contacting with each other to form separate adjacent vertical flues for the passage of air about the heating element and for inducing a rapid circulation of the heated air.

11. A radiator for heating the air of a room by steam or other high temperature heating medium comprising in combination a continuous tube extending horizontally lengthwise of the radiator and a radiating structure applied to the sides thereof and corrugated in horizontal section to form vertically grooved front and back surfaces of the height and width of the radiator, the inner portions of the corrugations substantially contacting with each other to form separate adjacent vertical flues for the passage of air about the tube and for inducing a rapid circulation of the heated air.

12. A radiator for heating the air of a room, having a horizontally extending heating element and a radiating structure applied to

the sides thereof, and corrugated in horizontal section, the inner portions of the corrugations substantially contacting with each other to form separate adjacent vertical flues for the passage of air about the heating element and for inducing a rapid circulation of the heated air and a panel extending across the front one of said vertically grooved surfaces forming the exposed front face of the radiator.

In witness whereof, I have hereunto signed my name.

THOMAS E. MURRAY, Jr.
